UNITED STATES PATENT OFFICE.

GEORGE C. KINDT, OF JERSEY CITY, NEW JERSEY, ASSIGNOR TO GEO. BORGFELDT & CO.,
OF NEW YORK, N. Y., A CORPORATION OF NEW JERSEY.

DESIGN FOR A SPUN METAL VESSEL.

47,793.

Specification for Design.

Patented Sept. 7, 1915.

Application filed February 11, 1915. Serial No. 7,606. Term of patent 3½ years.

To all whom it may concern:

Be it known that I, GEORGE C. KINDT, a citizen of the United States, residing in Jersey City, county of Hudson, and State of New Jersey, have invented a new, original, and ornamental Design for a Spun Metal Vessel, of which the following is a specification, reference being had to the accompanying drawing, forming a part thereof, and in which the figure is a perspective

side view of a spun copper vessel showing my new design.

I claim—

The ornamental design for a spun metal vessel as shown.

GEORGE C. KINDT.
